Term of patent 7 years

(CL D90—20)

Fig. 1

*Fig. 2**Fig. 3**Fig. 6**Fig. 5**Fig. 4*Fig. 1 is a perspective view of a tire embodying our new design; it being understood that the full line portion is repeated throughout the circumference of the tire shown by means of broken lines;

Fig. 2 is a fragmentary top plan view thereof;

Fig. 3 is a fragmentary side elevational view thereof;

Fig. 4 is a sectional view taken substantially along the line IV-IV of Fig. 2;

Fig. 5 is an enlarged fragmentary view taken substantially along the line V-V of Fig. 2; and

Fig. 6 is an enlarged fragmentary view taken substantially along the line VI-VI of Fig. 4.

The dominant feature of our design consists in the portions shown in full lines.

We claim:

The ornamental design for a tire, substantially as shown and described.
